UNITED STATES PATENT OFFICE.

JOSEPH J. STOETZEL, OF QUEENS VILLAGE, NEW YORK, ASSIGNOR TO G. & G. ATLAS SYSTEMS, INC., OF NEW YORK, N. Y., A CORPORATION OF NEW YORK.

SINGLE-TUBE PNEUMATIC-DISPATCH UNIT.

Application filed JUNE 9, 1926. Serial No. 114,651.

This invention relates to pneumatic dispatch apparatus of the type in which carriers are dispatched in either direction over a single line of tubing.

5 A general object of the invention is to provide a single tube pneumatic dispatch line apparatus in which a power saving minimum flow of air through the transmission lines is provided between carrier moving operation. The invention includes the provision of an air circuit or loop between the central station and each outlying station, the circuit including the transmission line and a conduit used solely to complete the 15 air circuit.

The invention includes means for producing a flow of air through the circuit referred to in either direction, means being provided in connection with the minimum air flow 20 controlling means for automatically producing a full carrier-impelling flow of air in one direction when a carrier is inserted in the transmission line. The same means is employed to automatically shut off the carrier- 25 impelling flow of air when the carrier emerges at either end of the line.

Another feature of the invention resides in the provision of a manually operable device for causing a carrier-impelling flow of 30 air to traverse the circuit or loop in the opposite direction, timing means being associated with the manually operable device for reestablishing the condition wherein the transmission line is adapted to convey carriers in the opposite direction upon the insertion of a carrier in the opposite end of the line.

Other features of the invention will be hereinafter referred to.

40 Referring to the drawings for a more detailed description of the invention;

Fig. 1 is a diagrammatic view of an operating unit of a pneumatic dispatch system, embodying the invention;

45 Fig. 2 is a view in vertical section of controlling devices used in connection with the dispatch apparatus shown in Fig. 1.

Referring to the drawings for a more detailed description of the invention, in Fig. 50 1 a pneumatic dispatch installation is shown which includes a central station A, an out-lying station B, a connecting carrier trans- mission line 5, a source of exhaust 6 and an air conduit 7 connecting the central station

with the outlying end of the transmission line 5.

Controlling apparatus is shown generally at 7 at the central station A for producing the operating effects hereinafter referred to. The controlling apparatus includes a valve 60 member 8 operating in a chamber 9 to control the direction of flow of air through the carrier transmission line 5 into the source of exhaust 6.

In the normal position of the valve 8, such as is shown in Fig. 2 of the drawings, a minimum flow of air is maintained through the transmission line 5 from the outlying end thereof at station B through the conduit 10 into the chamber 9 and thence through the pipe 11, through the restricted annular opening 12 between a control valve 13 and its seat 14, and thence through the pipe 15 to the source of exhaust 6. The air supply for the flow thus described enters the chamber 9 75 from atmosphere by way of the port 16 and thence flows through the air conduit 7 to the outlying end of the transmission line 5 at station B where it enters the transmission line at the connection 17 of the air conduit 50 7 with the outlying terminal of the carrier line 5.

With this condition of the apparatus, the insertion of a carrier by way of the gate 18 at station B into the carrier line 5 immediately produces a blocking or restricting effect on the slight flow of air taking place through the carrier line and thereby produces a partial vacuum or drop in pressure in the carrier tube ahead of the carrier. 90 This partial vacuum is communicated to a compartment 19 in the diaphragm chamber 20 by way of a port 21 in a wall member 22 separating the diaphragm chamber 20 and the valve chamber 23. The partial vacuum 95 thus established in the compartment 19 brings about the movement of the diaphragm 24 to its right hand position through atmospheric pressure produced in the compartment 25 by way of the port 26. The movement of the diaphragm 24 to its right hand position moves the valve member 13 to an opened position against the pressure of the spring 27. The full flow of air is thereby established by the connection thus produced 100 between the transmission line 5 at station A and the source of vacuum 6. The carrier is accordingly impelled through the

transmission line and is discharged at station A by way of the gate member 28.

The release of the vacuum or suction effect produced when the carrier emerges from the 5 transmission line at station A results in the movement of the diaphragm 24 to its left hand position shown in Fig. 2 through the action of the spring 27 which thereby again moves the valve member to its minimum flow 10 or closed position, as shown in this figure, thereby again establishing the normal condition which obtained before the carrier was inserted in the transmission line at station B.

In order to transmit a carrier through 15 the carrier line 5 from the central station A to the outlying station B, a carrier is inserted in the end of the line at station A by way of the gate 28. A manually operable valve control member 30 is thereupon actuated to remove a closure disc 31 from its seat on the end of a tubular member 32, a spring member 33 acting to immediately restore the disc 31 to its closing relation with the end of the tubular member 32 when the 25 member 30 is released. The opening of the closure disc 31 permits air to enter the tubular member 32 and pass through the pipe 33 into a cylinder 34 in which a piston member 35 is adapted to reciprocate. The 30 pipe 33 enters the upper end of the cylinder 34 whereas the lower end or part beneath the piston 35 is connected by way of a conduit 36 with the source of vacuum existing in the pipe connection 15.

35 The connection of the upper end of the cylinder 34 with atmosphere permits the suction applied beneath the piston 35 through the connection 36 to move the piston 35 downwardly against the pressure of a spring 37. The downward movement of the piston 35 carries with it the stem 38 and removes from closing relation with a port 39 a closing disc 40, thereby connecting the compartment 41 of a diaphragm chamber 42 with atmosphere. The compartment 43 at the other side of the diaphragm 44 in the chamber 42 is connected by way of a pipe 45 with the source of vacuum in the pipe 15 already referred to. The result of 45 opening the compartment 41 beneath the diaphragm 44 to atmosphere is to permit the source of exhaust in the pipe 45 to be applied to lift the diaphragm 44 against the pressure of the spring 46.

55 The upward movement of the diaphragm 44 carries with it the stem 47 which is connected through a link 48 with a crank arm 49 connected to the shaft 50 of the control valve 8 already referred to. The lifting 60 of the stem 47 rotates the valve 8 to its other or reverse position, thereby reversing the direction of flow of air through the carrier transmission line 5 in the following manner. In the new position of the valve 8 a flow of 65 air, instead of entering the valve chamber

9 by way of the conductor, enters by way of the air conduit 7. Also the connection to atmosphere at port 16 now communicates with the pipe 10 so that air entering at 16 from atmosphere travels upwardly through the pipe 10 to the transmission line at station A and thence through the line to station B whence the air returns through the air conduit 7, as already described.

It will be seen that with the reversal of position of the valve 8 and the reversal of the direction of flow of the air through transmission line 5, the insertion of a carrier in the line 5 at station A again produces the restricting effect already referred to and 15 brings about the automatic opening of the valve 13 in the manner already described. The flow of air thus established through the transmission line 5 from central station A to outlying station B is accomplished practically instantaneously and the carrier is immediately started on its journey through the line to station B. The emergence or discharge of the carrier at station B again establishes in the valve chamber 23 and connected compartment 19 of the diaphragm chamber 20 the release or break in vacuum which permits the spring 27 to move the valve 13 to its closing position whereupon a minimum flow of air is again established 25 in the transmission line 5 but in a contrary direction to that previously described.

In order to again restore the normal condition of the apparatus which, as already 30 stated, is that shown in Fig. 2 of the drawings, with the control valve 8 in the position shown therein, a timing device is employed which includes the cylinder 34 and its contained piston 35 already referred to. In addition, the cylinder 34 is provided with a control passageway 51 connected at its lower end with a port 52 leading to the compartment beneath the piston 35 and at its upper end through a port 53, whose size can be regulated by the adjusting screw 54, 35 to the compartment above the piston 35. With this construction and with the closure disc 31 of the control valve device in its closed position, the effect of the exhaust applied through the pipe 36 is to establish 40 pressure conditions of the same value on opposite sides of the piston 35, thereby permitting the spring 37 to lift the valve 35 to its elevated position in which the disc 40 is moved into closing relation to the port 39. The period of time required to bring about 45 this operation is predetermined and is regulated by means of the screw 54 to take place just following the period of time taken for a carrier to travel through the tube from station A to station B.

The closing of the port 39 again establishes identical pressure conditions on opposite sides of the diaphragm 44 by means of a controlled port 55 which provides a com- 50

5 municating passage between the upper and lower faces of the diaphragm 44. This condition permits the spring 46 to move the stem 47 downwardly to swing the valve 8 to its normal position shown in Fig. 2, thereby establishing the normal condition of the apparatus referred to.

10 The single tube carrier line through which carriers are transmitted in opposite directions, which is thus provided, affords a useful and economical installation in cases where carrier lines of large and unusual cross sections are employed, such as the oval section lines having in some cases a 15 thickness of three inches and a width of six inches. In such cases the air conduit line 7 which is employed may be of lesser dimensions and in the form of standard circular tubing, thereby providing an installation at 20 a relatively low cost.

What I claim is:

1. In a pneumatic dispatch apparatus, a carrier-transmitting line, a vacuum-producing device, means for connecting the 25 vacuum-producing device to either end of the carrier-transmitting line to thereby cause carriers to travel through the line in either direction, and means for establishing a minimum flow of air through the line between carrier-impelling operations.

2. In a pneumatic dispatch apparatus, a carrier-transmitting line, a vacuum-producing device adapted to be connected to one end of the carrier-transmitting line, an air 35 conduit adapted to connect the vacuum-producing device and the other end of the carrier-transmitting line, means for connecting the vacuum-producing means to either the air conduit or the carrier-transmitting line 40 to thereby cause carriers to travel through the transmitting line in either direction, and means for establishing a minimum flow of air through the transmission line toward the end of the line to which the vacuum-producing 45 device is connected between carrier-impelling operations.

3. In a pneumatic dispatch apparatus, a carrier-transmitting line, a vacuum-producing device, means for connecting the vacuum-producing device to either end of the carrier transmitting line to thereby cause carriers to travel through the line in either direction, and means responsive to the insertion of a carrier in one end of the tube 55 for establishing a carrier-propelling flow of air in the tube, said means being responsive to the break in vacuum produced when the carrier is discharged from the other end of the tube for cutting off the carrier-propelling flow of air.

4. In a pneumatic dispatch apparatus, a carrier-transmitting line, a vacuum-producing device, means for connecting the vacuum-producing device to either end of the 60 carrier-transmitting line to thereby cause

carriers to travel through the line in either direction, and a control device responsive to the insertion of a carrier in one end of the tube for establishing a carrier-propelling flow of air in the tube, said control device 70 being responsive to the break in vacuum produced when the carrier is discharged from the other end of the tube for cutting off the carrier-propelling flow of air and establishing a minimum flow of air through the line. 75

5. In a pneumatic dispatch apparatus, a carrier-transmitting line, a vacuum-producing device, valve means for connecting the vacuum-producing device to either end of the carrier-transmitting line to thereby cause carriers to travel through the line in either direction, a control device responsive to the insertion of a carrier in one end of the tube for establishing a carrier-propelling flow of air in the tube, said control device 80 being responsive to the break in vacuum produced when the carrier is discharged from the other end of the line for cutting off the carrier-propelling flow of air through the line and manually operable means for causing the actuation of said valve means to bring about a carrier-propelling flow of air through the transmitting line in the opposite direction. 85

6. In a pneumatic dispatch apparatus, a carrier-transmitting line, a vacuum-producing device, valve means for connecting the vacuum-producing device to either end of the carrier-transmitting line to thereby cause carriers to travel through the line in either direction, a control device responsive to the insertion of a carrier in one end of the tube for establishing a carrier-propelling flow of air in the tube, said control device being responsive to the break in vacuum produced 90 when the carrier is discharged from the other end of the line for cutting off the carrier-propelling flow of air and establishing a minimum flow of air through the line, and manually operable means for causing the actuation of said valve means to bring about a carrier-propelling flow of air through the transmitting line in the opposite direction. 95

7. In a pneumatic dispatch apparatus, a carrier-transmitting line, a vacuum-producing device, valve means for connecting the vacuum-producing device to either end of the carrier-transmitting line to thereby cause carriers to travel through the line in either direction, a control device responsive to the insertion of a carrier in one end of the tube for establishing a carrier-propelling flow of air in the line, said control device being responsive to the break in vacuum produced when the carrier is discharged from the other end of the line for cutting off the carrier-propelling flow of air and establishing a minimum flow of air through the line, manually operable means for causing the actuation of said valve means to bring about 100 105 110 115 120 125 130 135

a carrier-propelling flow of air through the transmitting line in the opposite direction, and timing means operating to reverse the position of the valve means after a predetermined interval of time.

8. In a pneumatic dispatch apparatus, a carrier-transmitting line, a vacuum-producing device, valve means for connecting the vacuum-producing device to either end of the carrier-transmitting line to thereby cause carriers to travel through the line in either direction, a control device responsive to the insertion of a carrier in one end of the line for establishing a carrier-propelling flow of air in the line, said control device being responsive to the break in vacuum produced when the carrier is discharged from the other end of the line for cutting off the carrier-propelling flow of air and establishing a minimum flow of air through the line, manually operable means for causing the actuation of said valve means to bring about a carrier-propelling flow of air through the transmitting line in the opposite direction, and said control device operating to cut off the carrier-propelling flow of air in said opposite direction and to establish a minimum flow of air through the line when a carrier is discharged from the line.

9. In a pneumatic dispatch apparatus, a carrier-transmitting line, a vacuum-producing device, valve means for connecting the vacuum-producing device to either end of the carrier-transmitting line to thereby cause carriers to travel through the line in either direction, a control device responsive to the insertion of a carrier in one end of the line for establishing a carrier-propelling flow of air in the line, said control device being responsive to the break in vacuum produced when the carrier is discharged from the other end of the line for cutting off the carrier-propelling flow of air and establishing a minimum flow of air through the line, manually operable means for causing the actuation of said valve means to bring about a carrier-propelling flow of air through the transmitting line in the opposite direction, said control device operating to cut off the carrier-propelling flow of air in said opposite direction and to establish a minimum flow of air through the line when a carrier is discharged from the line, and timing means operating to reverse the position of the valve means after a predetermined interval of time.

JOSEPH J. STOETZEL
